UNITED STATES PATENT OFFICE.

MURRAY H. CAZIER AND ERNEST P. YOUKEY, OF CHICAGO, ILLINOIS, ASSIGNEES, BY
MESNE ASSIGNMENTS, TO ALEXANDER ADERER, OF NEW YORK, N. Y.

CLOTHES-HANGER RACK.

Application filed November 4, 1920. Serial No. 421,701.

To all whom it may concern:

Be it known that we, MURRAY H. CAZIER and ERNEST P. YOUKEY, citizens of the United States, residing at Chicago, in the county of Cook and State of Illinois, have invented certain new and useful Improvements in Clothes-Hanger Racks, of which the following is a specification.

Our invention relates, in general, to garment hangers, and while adapted to be used promiscuously in connection with garments of either sex it is more particularly designed for hanging men's outer garments, as coats, vests and trousers.

15 The object of our invention is economy in space and convenience in hanging and removing garments.

In the accompanying drawing, which illustrates our invention—

20 Figure 1 is a perspective view showing the hanger in use.

Figure 2 is a side view of the supporting arm, hereinafter designated the hanger arm, and

25 Figure 3 is a transverse section of the hanger arm with a hanger depending therefrom.

Referring more particularly to the drawing, A designates the hanger comprising two 30 diverging arms a, a secured together at one end, as usual; or, if preferred, the hanger may be made with the two arms thereof integral with each other. The lower ends of the two arms are connected by a transverse 35 bar b for reception of folded articles, such as trousers, skirts, etc. As so far described the hanger does not differ materially from those in common use.

At its apex the hanger is provided with 40 means for suspending it from a supporting rod or arm B, said suspending means comprising a stud c projecting from the apex and formed with a head d.

The hanger arm B comprises a cylindrical 45 tubular member having at one end laterally extending perforated ears e by which it is conveniently attached to a wall or other support, and it has attached to its outer end a stay rod or bar f which extends inward and

50 upward and is provided at its inner end with means for attaching it above the arm B to prevent the latter from sagging or being pulled down.

The arm B has on its under side a slot g extending from end to end, and it has 55 formed in one side any desirable number of openings h connected by slots i with the longitudinal slot g, the openings h being of a size to receive the heads d of the studs c, and the width of the slots g and i being 60 such as to prevent the heads d from passing through.

The hangers may be applied to the arm B, either before or after the garments are placed thereon, by inserting the heads d into 65 the openings h, then turning them down until the studs c reach the longitudinal slot g, after which they may be moved along to any desired position on the arm B. The slot g being open at the outer end the hanger 70 may be applied from the end when the arm is taken up past the outer opening h.

It will be observed that a hanger may be applied to the arm B at any convenient point, either in front of, in rear of, or between other hangers previously applied, that the hangers may be moved into close relation with each other in order to economize in space occupied, and that there is practically no liability of accidental displacement of a 80 hanger from the arm B.

Having now described our invention we claim—

A clothes hanger rack comprising a tubular member provided with a longitudinal 85 slot in its bottom extending throughout its length and with a plurality of keyhole slots in its side communicating with said longitudinal slot, said tubular member having its outer end open, means for attaching one 90 end of said tubular member to a vertical support and maintaining it projected in a substantially horizontal position therefrom, and a brace for additionally supporting said open outer end, whereby clothes hangers 95 having headed shanks may be inserted and removed individually through the keyhole slots in the tubular member, or removed collectively through the outer open end of said tubular member.

100 In testimony whereof, we affix our signatures hereto.

MURRAY H. CAZIER.
ERNEST P. YOUKEY.
